(57) **CLAIM**

The ornamental design for a rotary waterfowl decoy, as shown and described.

DESCRIPTION

FIG. 1 is a perspective view of the invention;
FIG. 2 is a front elevation view of the invention;
FIG. 3 is a right side elevation view of the invention;
FIG. 4 is a rear side elevation view of the invention;
FIG. 5 is a left side elevation view of the invention;
FIG. 6 is a top plan view of the invention; and,
FIG. 7 is a bottom plan view of the invention.

The arms of the rotary waterfowl decoy are shown with a symbolic break in their length.

The appearance of any portion of the article between the break lines forms no part of the claimed design.

The broken lines in the drawings showing the rotary waterfowl decoy illustrate environment and forms no part of the claim.
